UNITED STATES PATENT OFFICE.

WILLIAM McCALLUM, OF SOUTH ORANGE, NEW JERSEY, ASSIGNOR TO THE BIGELOW CARPET COMPANY, OF CLINTON, MASSACHUSETTS.

DESIGN FOR A CARPET.

SPECIFICATION forming part of Design No. 13,333, dated October 10, 1882.

Application filed September 6, 1882. Term of patent 3½ years.

To all whom it may concern:

Be it known that I, WILLIAM McCALLUM, of South Orange, Essex county, New Jersey, have invented a new and original Design for 5 Carpets, of which the following is a specification.

This invention relates to a new and original design for carpets and similar fabrics; and it consists in the novel grouping and configuration of parts, hereinafter more fully described.

The accompanying photograph illustrates a face view of a carpet having my new design.

A is a stripe, composed of the band *a*, ornamented with a series of connected diamond-shaped figures, below which runs the band *b*, containing an ornamentation of patterned figures consisting of upright stems, terminating at one end in circular figures and at the other in rectangular figures, and set alongside each other in a row. The stripe A also contains the band *c*, ornamented with a series of panels containing diagonal stripes, alternating with panels each of which contains a vine-like figure.

The stripe B is composed of a band, *d*, at its 25 upper portion, which is separated from the lower part of the stripe by a line of molding, *n*. The stripe B contains the figure D, consisting of a flower group composed of the figures *r*, *s*, *i*, and *h*, consisting of flowers of various forms, and contained within a line in the 30 form of an open arch, having a step-like projection, *f*, about half-way up on each side.

The figure *g* is a flower bunch apparently resting on the step-like projection *f*. The figure *e* consists of two branches, crossing each other 35 and extending over into the band *d*. The band C extends below the stripe D, and is ornamented with a series of leafy vine-like branches.

I claim—

1. The design for carpets, consisting of the band *b*, substantially as shown.
2. The design for carpets, consisting of the band *c*, substantially as shown.
